UNITED STATES PATENT OFFICE.

GEORGE W. PRICE, OF BALTIMORE, MARYLAND, ASSIGNOR OF ONE-HALF
TO WILLIAM J. HOOPER, OF SAME PLACE.

STEAM-ENGINE.

SPECIFICATION forming part of Letters Patent No. 337,518, dated March 9, 1886.

Application filed June 26, 1885. Serial No. 109,806. (No model.)

To all whom it may concern:

Be it known that I, GEORGE W. PRICE, of the city of Baltimore and State of Maryland, have invented a new and useful Improvement 5 in Steam-Engines, of which the following is a full description, which will be readily understood by referring to the accompanying drawings, of which—

Figure 1 is an upright sectional view of the engine, the cylinders on the steam side being shown partly in full and partly broken away. It also shows the two cranks on that side of the figure, one up and the other down, and on the right they stand horizontally on opposite 15 sides of the shaft. This figure also shows the pistons to correspond in position with the cranks. Fig. 2 shows an end view of the machine, partly in section, and showing the four cranks with their connecting-rods in dotted 20 lines. Fig. 3 is a top view of the machine. Fig. 4 is an upright sectional view of the apparatus, showing the same position of pistons and cranks as in Fig. 1, and the ports in the cylinders and steam-passages. Figs. 5, 6, and 25 7 are views of the same, showing different positions of the piston and the steam and exhaust passages. Fig. 8 is an upright sectional view of an apparatus in which are shown hollow or recessed pistons, illustrating a method by 30 which the steam may be introduced from the side instead of at the tops of the cylinders, and having the same arrangement of steam and exhaust passages. Fig. 9 is a sectional end view of one of the cylinders as shown in Fig. 8.

35 My invention relates to that class of steam-engines in which the piston is used as a valve to open and close the steam-ports; and it consists in a novel arrangement of ports and passages, whereby I am enabled to use an ordinary plain piston and provide but two ports in each cylinder to be opened and closed by the piston in passing.

Let A, B, C, and D represent the cylinders, and a, b, c, and d their respective pistons. In 45 the cylinders A and B, I provide the ports a' and b', located about midway of the stroke of the respective pistons, and construct them about equal in length to the thickness of their respective pistons. From the port a' in cylinder A, I construct a passage-way, which I have marked a c, which leads to a port (marked c') which opens in the bottom of cylinder C, and from the port b' in cylinder B, I construct a similar passage-way (marked b d) leading from said port to the port marked d', which 55 opens in the bottom of cylinder D. In cylinders C and D, I have provided a similar arrangement, the ports c' and d' being for convenience located on the opposite side of said cylinders, though this is not necessary, as they 60 would work just as well on the same side as the ports of cylinders A and B. These ports c' and d' are shown in dotted lines in Figs. 4 and 6, and partly plain and partly dotted lines in Figs. 5 and 7, according to whether 65 they are exposed or covered by the position of the piston. From the port c' in cylinder C, I construct the passage-way marked c a, which leads to the port a', opening in the bottom of cylinder A, and from the port 70 d' in cylinder D the passage-way d b to the port b', opening in the bottom of cylinder B. The cranks pertaining to each cylinder and piston I have marked, respectively, a³ b³ c³ d³, and the connecting-rods a⁴ b⁴ c⁴ d⁴, which are 75 pivoted to the piston and connected directly with the cranks. Thus it will be seen that each cylinder has but two ports or openings, one located about midway of the stroke of its piston and the other at the bottom. It will 80 also be seen that each of the ports located about midway communicates with the cylinder next but one from it, and at the bottom—that is to say, cylinder A is connected from at or near the middle to the bottom of cylinder c. Cylinder B is connected in the same way with cylinder D, cylinder C is connected in the same way with cylinder A, and cylinder D with cylinder B. The purposes and uses of making 85 these connections in this way will be explained 90 more fully hereinafter in describing the mode of operation of the machine. From the tops of these cylinders I have cast or otherwise secured the steam-tight box or chest E, which runs from the cylinders up to the shaft F and furnishes the means for supporting said shaft. This steam-chest is divided by the steam-tight 95 partition-wall G, which separates the chest into two compartments, thus leaving two cylinders located on each side of the partition- 100

wall G. A cover, H, is then secured to the steam-chest, of such shape and form as to continue the compartments thus formed, and the stuffing-boxes e and journal-bearings f are thus formed in two halves, one half upon the walls of the steam-chest and the other upon the corresponding walls of the cover, as shown in Fig. 1. The cover is provided with the openings I and I', one of which may be used as an inlet and the other for the exhaust of the steam. Either may be so used, as matter of choice; but in order to explain I have chosen to select the opening I as the steam-inlet, and I' as the exhaust.

Let us first take Fig. 1, with the positions of the pistons as shown in that figure, and allow the steam to enter the opening I in the cover: the pressure of steam would be primarily upon the tops of the two pistons a and b; but as piston b is below the top of port b' the steam passes out of said port through the passage b d and has entered cylinder D below the piston d. Piston b being at the bottom of its stroke and just ready to move upwardly, it would encounter the full pressure of steam against it, were it not for the fact that piston d is also running upwardly, and just at this point is beginning to uncover the port d', allowing the steam to pass out through the passage-way d b into the bottom of cylinder B and below piston b, thus counterbalancing the pressure of steam on the other side of that piston. Now the condition of the pistons as to pressure would be as follows: Piston a, which is just ready to begin its downward movement, will have a full head of steam upon it direct, piston d, which is moving upwardly, will have a full pressure of steam upon it below, and piston b will be counterbalanced by a pressure of steam on both sides.

Before leaving Fig. 1 it would be well to explain the exhaust as it occurs in that position of the pistons. Two of the four cylinders are exhausting—cylinders A and C. Piston a is just beginning to move downwardly, and its cylinder is just beginning to exhaust. The steam which has forced piston a to the top of its stroke now begins to exhaust through the port a' and passage-way e a out through port c', which is just being uncovered by the downward movement of piston e, and up through the opening I', and cylinder C (whose steam has followed the piston a since the descent of its piston began) now exhausts through its lower port, e', and passage-way a c into cylinder A, and out through port a' and passage-way e a above piston e through the exhaust-opening I'.

In Fig. 6 the positions of the pistons are exactly reversed. Piston a is just beginning its upward movement, piston b just beginning to come down, piston e, at about half-stroke, moving upwardly, and piston d, in about the same position, moving downwardly. The pressure of steam here, as always, is upon the tops of the two pistons a and b; but it has passed out of cylinder A through the port a' and entered

below piston e through the port c'. It is now beginning to pass out of the port c' into the port a', and is counterbalancing the piston a, 70 the cylinders B and D are exhausting, the piston b is forcing the steam through the exhaust, and d' out through the exhaust-opening I, and the piston d is forcing the steam below it through the ports d' and b' into cylinder B, 75 and out through b' and d' to the exhaust-opening I'. The position of the pistons as to pressure is as follows: Piston a is counterbalanced, piston b has full pressure of steam on top to force it down, and piston d has full pressure 80 of the steam below to force it up.

It will now only be necessary to notice Figs. 5 and 7, showing pistons a and b at half-stroke and pistons c and d at full-stroke. These two figures have the positions of their cranks reversed. In Fig. 5 the crank of piston d is up and that of piston e down. In Fig. 7 the crank of piston c is up and that of d down. Now, if we follow the course of the steam and exhaust while the pistons are in these positions, it will be seen that the steam, as usual, is at full pressure on the tops of pistons a and b; that it is just beginning to pass out of cylinder A and enter below piston e, which is about commencing its upward movement; that the port b' is just closed off, which has let the steam into cylinder D to force piston d' to the top of its stroke and back again to counterbalance piston b. It will also be seen that piston d is just beginning to descend and force the steam 100 below it under piston b, and that piston b is just beginning to open port b' below and allow the exhaust-steam from cylinder d to enter, following piston b up as it ascends until piston d goes down far enough to open port d' at 105 the top and allow both B and D to exhaust.

To describe Fig. 7 will only be necessary to reverse the description just given.

It will thus be seen that the engine, as constructed, operates the pistons a and b from the top and c and d from the bottom; that cylinders A and B exhaust direct through C and D, and C and D exhaust through A and B and back again, each over its own respective piston.

The ports and passage-ways of Figs. 8 and 9 are arranged and operate in the same way. The pistons in each of these cylinders have hollow spaces or recesses between their heads, which spaces act as steam-chests. Instead of having the pressure of steam upon the top of the two pistons a and b, the engine is arranged without the steam-chest and cover above, leaving the shaft and cranks exposed.

The steam in the cylinders, Fig. 8, enters by 125 the port at the side. As the engine stands in the figure, piston a is at the top of its stroke and the steam occupies the space in the recess between its heads, piston b has passed down below the port b', and the steam has passed 130 out of that and is operating piston d from below, which is on its upward movement, and is just beginning to open the port d' and allow the steam to enter below piston b, which is

just beginning its upward movement, cylinders A and C are exhausting, A through the passage c^1 into the recess of piston c , and out through the exhaust, and cylinder C 5 through the port c^2 into cylinder A below piston a , out through a^2 , passage-way $c^1 a$, into the recess of piston c and the exhaust-pipe.

The passages for the steam and exhaust are just the same and operate in the same way as 10 those heretofore described; but all of the pistons are operated by pressure of steam upon the bottoms of the pistons.

The advantages of the special construction 15 shown and described are many. It is the cheapest form of engine in my knowledge, and will occupy little space when constructed.

What I claim, and desire to secure by Letters Patent, is—

1. In a steam-engine, two companion cylinders, as A and C, each having two ports, as a' and a^2 , c' and c^2 , and one piston, arranged, combined, and operating with the ports and each other, so that a portion of the steam operating on top of the piston in cylinder A may pass 25 out the port a' when piston a has descended to open said port, and into its companion cylinder C and below the piston c to force said piston upwardly and pass out of the port c' when the piston c has uncovered the lower 30 end of said port, back into cylinder a at the bottom, and under piston a , to counterbalance

the steam on the opposite side of said piston during its upward stroke.

2. In a steam-engine, two companion cylinders, as A and C, each having two ports, as a' 35 and a^2 , c' and c^2 , and one piston, arranged, combined, and operating with the ports and each other, so that the steam first enters cylinder A, and passes thence to cylinder C, and under piston c , to propel said piston, and out 40 of cylinder C back again to cylinder A, and under piston a , to propel it, substantially as shown and described.

3. In a steam-engine, two companion cylinders, as A and C, each having two ports, as a' 45 and a^2 , c' and c^2 , and one piston, arranged, combined, and operating with the ports and with each other, so that the steam from cylinder A will exhaust through cylinder C direct, and the steam from cylinder C will exhaust through 50 cylinder A, and then back through cylinder C on the opposite side of its piston.

4. A steam-engine having two or more pairs of cylinders, one half of which have their pistons exposed to direct pressure of the steam on top, and the other half arranged to receive the pressure of steam on the bottom, substantially 55 as described.
